TRAPEZE AND FLYING RINGS

Filed March 23, 1932

INVENTOR.

Florence E. Mayo,
BY John G. Barbaro

ATTORNEY .

UNITED STATES PATENT OFFICE

FLORENCE E. MAYO, OF JAMAICA, NEW YORK

TRAPEZE AND FLYING RINGS

Application filed March 23, 1932. Serial No. 600,790.

My invention relates to trapezes and flying rings which are mounted so as to be adapted for diversified movement while the performer is using them. More particularly, 5 **5** my invention relates to trapezes and flying rings which are adapted to be rotated while being moved laterally back and forth above a stage and/or while being moved upwardly and downwardly above the stage. By "moved laterally" I refer to movement crosswise of the stage, that is, movement toward either side, the front or the back thereof, including oblique movement. I provide a mounting for the trapeze and flying rings which comprises 10 **10** a carrier having means for rotating the trapeze and flying rings, a flexible support along which the carrier is adapted to travel back and forth across the stage and which is movable upwardly and downwardly above the stage, and means for moving the carrier along this support. My invention also comprises 15 **15** novel and effective means for rotating the trapeze and flying rings.

The principal object of my invention is to 20 **20** provide a trapeze and flying rings set adapted for movements such that performance thereon will be very spectacular and amusing and will hold the interest of a theatrical audience. This effect is attained because of 25 **25** the variety of movements provided by my apparatus. A secondary object is to provide a device requiring more skill on the part of the performer than the usual forms of trapeze and flying rings. My invention therefore is useful for both amusement and gymnastic purposes.

My invention consists primarily in the organization of elements whereby the various elements cooperate to produce a combination 30 **30** of several elementary movements, and partly in the elements per se, as will be apparent from the following description of an illustrative form of my invention and from the claims. My invention is illustrated in the 35 **35** accompanying drawing, in which:

Figure 1 is an elevation of my apparatus, a part of the cover for the rotating mechanism being cut away to show better the relation of parts.

50 **50** Figure 2 is a fragmentary elevational view

showing the position of the carrier and trapeze and flying rings when the carrier has been moved near one of the extremities of its lateral movement.

Figure 3 is an elevation of a motor and speed reducing gear for rotating the trapeze and flying rings, a part of the cover for the motor and gear being cut away.

Figure 4 is a top plan view of the elements shown in Figure 3.

In the particular form of the invention shown in the drawing, 1 is a three-wheel pulley and 2 is a two-wheel pulley over which a cable or other suitable flexible supporting member 3 is passed. As shown, the pulleys 1 and 2 are supported by chains C from the beam B, or other usual means for supporting scenery or apparatus in a theater, but it is obvious that these pulleys may be secured to a ceiling, side walls or any other sufficient support. 70 The end 4 of cable 3 is fixed to any suitable immovable member, while the end 5 is fastened to a block 6 which receives operating cable 7 controlled by any suitable device 8, which may be one having such mechanical advantage as to permit of manual operation. On cable 3, between pulleys 1 and 2 and by means of pulley wheels 9, is supported a carrier 10, to the upper part of which are secured two ropes or lines 11 and 12 for moving the carrier along cable 3. From carrier 10 line 11 passes over one wheel of pulley 1 and down toward the floor of the stage or other place where the apparatus is being used. Line 12 passes from the carrier over the second wheel of pulley 2 and then over the remaining wheel of pulley 1 toward the floor. By this arrangement, it is obvious that a single operator may readily manipulate lines 11 and 12, which are conveniently termed "short line" 90 and "long line", respectively. It is also apparent that a plurality of single wheel pulleys may be used instead of the multiple wheel pulleys 1 and 2.

On the base plate 13 of the carrier 10 is mounted a prime mover 14, which preferably is an electric motor and which is adapted to rotate the trapeze and flying rings set 15 through speed reducing gear. The rotation of the set is normally about a substantially 100

vertical axis, the deviation therefrom increasing as the carrier approaches the lateral extremities of its movement, as shown in Figure 2. The speed reducing gear comprises 5 a worm 17 secured to the motor shaft by means of any suitable coupling 16, which permits the worm 17 to be made as a member separate from the motor shaft, a gear 18 engaging worm 17, a worm 20 on a shaft 19 10 which is common to gear 18 and worm 20, and a gear 21 meshing with worm 20. Shaft 19 is mounted in supports 22 carried by base plate 13. Gear 21 is fixed to shaft 23 which passes through a suitably bushed opening in 15 plate 13 and which is provided with a collar 24 to maintain shaft 23 in proper relation with plate 13, whereby gear 21 is kept in mesh with worm 20. It will be noted that there are two stages of speed reduction in this 20 mechanism, namely, a first between worm 17 and gear 18, and a second between worm 20 and gear 21. A cover 25 is provided for this mechanism and the motor 14. The shaft 23 terminates in a perforated flattened lower 25 end, to which is secured, as by bolts 26, the trapeze and flying rings set 15. This set may be of any suitable form, and is here shown as including both rings 27 and trapeze 28; it is obvious, however, that the set may consist of 30 only the trapeze, or only the flying rings, or both, and it is in this broad sense that the term trapeze and flying rings set is employed in the claims. Of course, the trapeze and rings may be separate elements instead of being 35 connected together in the manner shown in the drawing. Control of this set 15 is completed by an electric cable 29 which runs from motor 14 over pulley 30 to control switch 32, by means of which any one of several speeds 40 of rotation of the set 15 may be selected. Preferably, but not necessarily, cable 29 is maintained taut by any suitable reeling device 31. Pulley 30 may be supported in any suitable manner, as by a chain C' from beam 45 B.

The operation of my apparatus is as follows: The carrier 10 and set 15 are lowered, by operation of device 8, sufficiently for the performer to reach set 15, which is then raised 50 a suitable height above the stage. The carrier, and consequently the set 15, are moved back and forth across the stage by manipulation of "short line" 11 and "long line" 12, while set 15 is rotated at a speed selected by 55 means of switch 32. Set 15 may be given a vertical movement, additional to that resulting from movement along cable 3, by operation of device 8; or such vertical movement may be given set 15 without the lateral movement. Because of the constant change in 60 inclination of carrier 10 and set 15, due to movement along a flexible support such as cable 3, as shown by Figures 1 and 2, the means for rotating set 15 is mounted on the carrier 10, 65 whereby, except for the necessary reduction

in speed, direct application of rotative force of the prime mover 14 to the set 15 is obtained. It will be readily seen that, with my apparatus, set 15 may be given simultaneously rotary, lateral and vertical movements, and various paths of movement, by suitable operation of the various controls. 70

I claim:

1. In combination, a trapeze and flying 75 rings set, means for supporting said set in a suspended position, means for moving said set laterally while supported by said first-mentioned means, and means for rotating said set while being moved by said second-mentioned means. 80

2. In combination, a trapeze and flying 85 rings set, means for moving said set up and down, means for moving said set laterally back and forth while supported by said first-mentioned means, and means for rotating said set while being moved by said second-mentioned means.

3. In combination, a trapeze and flying 90 rings set, means for supporting said set in a suspended position and for moving said set laterally back and forth, and means for rotating said set while being supported and moved by said first-mentioned means.

4. In combination, a trapeze and flying 95 rings set, means for supporting said set in a suspended position and for moving said set laterally back and forth in a curved path, and means for rotating said set while being supported by said first-mentioned means.

5. In combination, a trapeze and flying 100 rings set, means for supporting said set in various inclined positions, means for moving said set laterally back and forth while supported by said first-mentioned means, and means for rotating said set while being moved by said second-mentioned means. 105

6. In combination, a trapeze and flying 110 rings set, means for moving said set laterally back and forth, means for supporting said set in varying inclined positions as it is moved back and forth, and means for rotating said set while being moved back and forth.

7. In combination, a trapeze and flying 115 rings set, means for moving said set laterally back and forth, means for moving said set up and down and for supporting it in varying inclined positions as it is moved back and forth, and means for rotating said set while being moved by said first-mentioned and second-mentioned means. 120

8. In combination, a trapeze and flying 125 rings set, a carrier for supporting said set, means for moving said carrier back and forth, means for supporting said carrier so that said set assumes positions of varying inclinations as it moves back and forth, and means for rotating said set while said carrier is moving back and forth.

9. In combination, a trapeze and flying 130 rings set, a carrier for supporting said set

in a suspended position, means for rotating said set, flexible means for supporting said carrier, and means for moving said carrier back and forth along said flexible means.

5 10. In combination, a trapeze and flying rings set, a carrier for supporting said set in a suspended position, means for supporting said carrier and for moving it back and forth in a curved path, and means for rotating said 70 set.

10 11. In combination, a trapeze and flying rings set, a carrier for supporting said set in a suspended position, means on said carrier for rotating said set, and means for moving 75 said carrier up and down and laterally back and forth.

15 12. In combination, a carrier, means for suspending said carrier above a stage, means for imparting to said carrier in its suspended 80 position a reciprocating movement, a trapeze and flying rings set carried by said carrier, and means on said carrier for rotating said trapeze and flying rings set during said reciprocating movement.

20 13. In combination, a carrier, means for lowering and raising said carrier above a stage, said means being also adapted to support said carrier in various positions above the stage, means for moving said carrier back and forth across the stage, a trapeze and flying 85 rings set suspended from said carrier, and means on said carrier for rotating said set, said last-mentioned means including a prime mover.

25 14. In combination, a carrier, means for lowering and raising said carrier above a stage, said means being also adapted to support said carrier in various positions above the stage, means for moving said carrier back and forth across the stage, a trapeze and flying 90 rings set suspended from said carrier, and means on said carrier for rotating said set about a generally vertical axis, said last-mentioned means including an electric motor and speed reducing gearing.

30 15. In combination, a trapeze and flying rings set, a carrier supporting said set in a suspended position, the upper part of said carrier having pulley wheels, a cable passing 95 under said pulley wheels, said cable passing over fixed pulleys on opposite sides of said carrier, means for moving said carrier along said cable between said fixed pulleys, and means on said carrier for rotating said set.

35 16. In combination, a trapeze and flying rings set, a carrier rotatably supporting said set in a suspended position, the upper part of said carrier having pulley wheels, two multiple-wheel pulleys fixed in spaced relation to each other, a cable passing under the carrier pulley wheels and over a wheel of each fixed pulley, the ends of said cable being secured against movement except when up and down movement of the carrier is desired, a rope secured to said carrier and pass- 100

ing over a wheel of one fixed pulley for moving said carrier laterally in one direction, a second rope secured to said carrier and passing over a wheel of each fixed pulley for moving said carrier laterally in the opposite direction, a prime mover on said carrier, and speed reducing gear connecting said prime mover and said set.

17. In a device of the class described, a trapeze and flying rings set, a carrier for said 75 set, flexible means for supporting said carrier, means for moving said carrier along said flexible means, and means on said carrier for rotating said set, said last-mentioned means including an electric motor and speed reducing 80 mechanism.

18. In a device of the class described including a carrier, a trapeze and flying rings set adapted to be suspended from said carrier, flexible means for supporting said carrier, and means for moving said carrier back and forth on said flexible means; means on said carrier for rotating said set, said last-mentioned means comprising an electric motor and speed reducing mechanism positively 90 connecting said motor and said set.

19. In a device of the class described including a carrier, a trapeze and flying rings set adapted to be carried by said carrier, means for supporting said carrier, and means 95 for moving said carrier back and forth on said first-mentioned means; means adapted to rotate said set and mounted entirely on said carrier, said last-mentioned means including a prime mover.

Signed this 21st day of March, 1932.
